ELECTRICAL SWITCHING MEANS

Henry J. McCarthy, Danvers, Mass., assignor to
 Sylvania Electric Products Inc., a corporation
 of Massachusetts

Application March 13, 1942, Serial No. 434,627

1 Claim. (Cl. 200—60)

The present invention relates to portable electric illuminating devices. It relates more specifically to means for controlling and limiting their light output in compliance with rules and regulations promulgated for public safety in time of blackouts.

When an air raid is taking place in a thickly settled district it is often necessary for civilians to find their way to places of safety in complete darkness. Others must be abroad patrolling and inspecting damages inflicted by bombs. Many others must carry on in various official capacities. Because promiscuous and indiscriminate showing of lights would communicate valuable information to enemy aircraft, it is considered both dangerous and unlawful to have a source of light that can be seen above the horizontal. However, in such times of stress it is entirely possible that one might unintentionally shine a light upwards, particularly in the case of rescue workers who must both carry on their work and provide their own light. Furthermore a dropped light might continue to burn in a vertical position.

Various systems of masking and dimming flashlights have been employed to minimize the danger of showing excessive light. There has not been any means thus far devised which will keep the light from shining when a flashlight is so disposed that the lens is directed upwardly. Therefore, an object of my invention is to provide a practical means for breaking the electrical circuit between the light and its power source, thereby extinguishing the light when said light is handled in such manner as to expose direct rays so that they may be seen from above. Another object of my invention is to have the switching means automatic so that it is completely foolproof. An advantage of my invention is that it is extremely compact, adding no bulkiness whatsoever to the device. Further it may be incorporated into any portable illuminating device commonly in use. This may be done simply, by anyone, as it does not require technical knowledge to install. Finally, it may be made and sold economically. Still other objects and advantages will be apparent from the following specification taken in conjunction with the accompanying drawing in which:

Figure 1 is a side elevation partly in section of the bulb socket of an ordinary flashlight and the cutout of my invention incorporated therein.

Figure 2 is a cross sectional view of a modification of said cutout.

Figure 3 is a perspective of said cutout.

My invention may be employed by removing the bulb from any flashlight, inserting the cutout into the bulb holder, and replacing said bulb. As

shown in Figure 1, the cutout 1 is placed in the socket 4 between the bulb 2 and the terminal 3.

The cutout 1, shown in section, is comprised of the drive screw contact 5, the metal plug contact 6 and the insulator 7. Enclosed in the chamber formed by the plug and the insulator is a drop of mercury 8. The size of this drop of mercury, the length of the drive screw, and the angular disposition of the portion of the chamber wall formed by the insulating member determine the angle at which the cutout will break the circuit by means of the mercury 8 rolling away from the drive screw 5 breaking the contact between contact 5 and the plug 6. Since a flashlight bulb gives only a feeble glow unless directionalized by means of a reflector and lens, it is reasonable to consider the direction of its light output synonymous with its longitudinal axis so that the beam of light will be projected in the same direction as the angle or plane which the longitudinal axis assumes.

In Figure 3, the cutout 1 is shown in perspective, element 5 being the head of the drive screw and element 6 the metal plug contact.

In Figure 2, the plug 6 and the drive screw 5 are altered to accommodate a substitution of material used for element 8. As above disclosed said element 8 is a drop of mercury. However, it may be found desirable to substitute a silver-plated ball. In such a case element 6 would have a lip on its edge which would also be silver-plated. This structure, in conjunction with a beveled edge on element 5, would tend to improve the contact through element 8. In such a case the angle at which the cutout would take effect is controlled by the pitch of the lip of element 6.

What I claim is:

In combination with a socket and an electric lamp having a sleeve-like outer contact member and an axial inner contact member, a control unit detachably received in said socket comprising a cylindrical body member of insulating material having a recess in each end connected by an axial aperture, the recess adjacent the lamp being of inwardly convergent conical form, a conductor extending through and having threaded engagement with said axial aperture, said conductor having a head seated in said conical recess and engaging said axial lamp contact member, said conductor projecting into said other recess, a cup shaped contact member having its rim portion extending into said other recess into close proximity to said conductor, and a mobile body of conductive material within said cup shaped contact of sufficient size to bridge the space between said contact and said conductor when said unit is in a particular range of positions.

HENRY J. McCARTHY.
